UNITED STATES PATENT OFFICE.

WILSON E. WEATHERLY, OF CHICAGO, ILLINOIS, ASSIGNOR TO AUSTIN G. BLAND, OF RIVERTON, WEST VIRGINIA.

AMPLIFYING ATTACHMENT FOR HORMS OF SOUND-REPRODUCING INSTRUMENTS.

Application filed October 13, 1926. Serial No. 141,351.

My present invention relates to the provision of an amplifying attachment for the horns of sound reproducing instruments. While my attachment may be employed with advantage in a suitable case with any such horn, it was designed more particularly for use with the invention disclosed in United States Letters Patent No. 1,363,482, dated December 28, 1920. By reference to this patent it will be seen that the horn therein employed is a convolute sea shell or conch. The horns in such instruments are in themselves amplifying elements. That is to say, the horns not only direct the sound as may be desired, but, also, by reason of holding a particular body of air in a particular relation to the vibrating diaphragm of the sound reproducing instrument the air within the horn is caused to vibrate so that the vibrations are transmitted to the exterior air much more effectively than they are or can be directly from the diaphragm without the horn. This being so it will be further appreciated that different kinds and particularly strengths of sound can be more effectively radiated by the selection of a horn of a particular kind and especially size. A sound of the intensity of conversational speech can be most effectively handled with a horn of relatively moderate size, whereas sound of the same intensity would be practically lost in a relatively large horn. And, conversely, a sound of great volume, or vibrations of relatively large amplitude capable of producing sound of great volume, cannot be effectively handled by a horn of relatively small size. With sound reproducing machines employing an undulatory record the range of the intensity of sound was not great and a single horn very satisfactorily covered the entire range. With the introduction of electrical amplification, however, vibrations of such an amplitude are produced that they cannot be most effectively handled by horns of the size employed on machines of the phonograph type. It is now not at all uncommon to attach electrical sound reproducers, or what is known as "loud speakers", to phonograph horns, and in such cases my invention may be advantageously employed. When a conch shell is employed as an amplifying horn, as described in the aforementioned patent, however, my invention is necessary in order to secure a high effi-

cency, as the organism which produces the shell definitely fixes its size and characteristics and the latitude of size between different shells from which selection may be made is not great.

I have found that the capacity of a horn for efficiently handling sound of a louder volume than it otherwise could do can be increased by increasing the length of the column of air included within the horn space without otherwise altering the size or shape of the horn, and that this holds good throughout rather definite limits, say, up to a length of twenty feet of horn space. This remains relatively true no matter whether the added length of column of vibrating air be tapered or cylindrical and no matter whether it be coiled or straight.

I have increased the efficiency of amplifying horns for handling strong sounds by means of the structures illustrated in the accompanying drawing, in which

Fig. 1 is an elevation of a sound reproducing or loud speaker unit, an amplifying attachment, and a conch in assembly, the amplifying attachment being shown partially in section;

Fig. 2 is a top plan of the amplifying attachment with the top removed;

Fig. 3 is a perspective of an adapter for bringing the location of the assembly between the amplifying attachment and the conch to the center of the amplifying attachment when that may be desired;

Fig. 4 is an elevation of an assembly when the adapter is employed; and

Fig. 5 is an elevation of an assembly in which a modified straight instead of coiled form of amplifier is employed.

Similar reference characters are employed to designate similar parts throughout the several figures.

I have schematically shown at 10 a form of sound reproducing or loud speaker unit resting on a base, 11, and having in the center of its upper face an aperture for the radiation of vibrations set up or created within the unit. Extending upwardly from the aforesaid aperture is a short length of tube forming an annulus, 12.

Fitting around the annulus 12 is another annulus or collar, 13, secured around a central opening to the lower face or bottom of a cylindrical casing, 14, closed by a top or

cover, 15, secured thereto by screws, 16, and adjacent the edge whereof is an opening surrounded by a hollow embossment or annulus, 17.

5 Mounted within the casing 14 with its ends in communication respectively with the openings surrounded by annuluses 13 and 17 is a coiled tube, 18.

10 The small end of a conch, 19, is apertured, and may be cemented directly into the annulus, 17, or into an open ended ferrule, 20, which fits into the annulus 17 or 19^a, as shown in Fig. 5.

15 The above described construction will function satisfactorily, but in order to give the assembly a more symmetrical appearance, and also to bring the weight of the conch more nearly over the base, 11, and thereby increase the stability, I have provided the adapter 20 shown in Fig. 3, which consists of an apertured base plate, 21, which is or may be secured to the top 15 of the amplifier casing 14.

Upon the top of the plate 21 is a hollow development or embossment 22, the cavity 25 whereof communicates with the opening in the plate 21 and extends therefrom to the opposite side of the plate, the said embossment terminating in an upstanding socket 23 communicating with the cavity within the 30 embossment, and into which socket the small apertured end of the conch 19 sets.

35 In Fig. 5 I have illustrated a modified form of amplifying attachment in which the tube 18^a is not encased but extends upwardly from its annulus 13^a. I have shown the tube 18^a slightly flared as it extends upwardly but this is not important so far as the sound effects are concerned and is done to provide a sufficient area at the top to accommodate the

annulus 14^a into which the small apertured 40 end of the conch 19, or the ferrule 20, fits.

What I believe I have contributed to the art is the knowledge that the flared outer end or horn of the sound conduit is the important feature so far as tonal effects are concerned 45 and that the length of passage included in or contiguous to and communicating with the horn is most effective in adapting the horn for efficiently handling different volumes or intensities of sound, and that I have utilized 50 these principles in providing an auxiliary amplifying element adapted to be inserted between the sound reproducing element and the flared or horn portion of the sound conduit.

55 It will be seen that in the form shown in Figs. 1 and 4 the sound proceeds from the loud speaker element 10 through the curved tube 18, to and through the horn 19, and that in the construction shown in Fig. 5, the sound proceeds from the loud speaker element 10 60 through the amplifying attachment 18^a to and through the conch 19.

Having described my invention what I claim as new and desire to secure by Letters Patent is—

65 An attachment for lengthening the volume of air included within an amplifying horn comprising a base having a chamber for the reception of a loud speaker unit therein, a stub tube rising from said base and having 70 communication with the chamber therein, a casing having apertures therein, collars surrounding said apertures and adapted to receive respectively said stub tube and the small end of an amplifying horn, and a coiled tube 75 within said casing having communication at its ends with said apertures.

WILSON E. WEATHERLY.
